UNITED STATES PATENT OFFICE.

KARL S. HOWARD, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE STRUCTURE.

Application filed August 18, 1926. Serial No. 129,932.

My invention relates to railway rolling stock and consists in an improved bed structure particularly adapted for electric locomotives in which a motor mounted on the bed is operatively connected to the driving wheels.

Many of the features of my invention may be utilized in a locomotive in which the motor is energized from a power line paralleling the track and I contemplate the exclusive use of these features in such a locomotive. However, my invention is most fully developed when embodied in a locomotive which generates its own current by means of an internal combustion engine of any familiar type, such as the Diesel engine.

One of the objects of my invention is to simplify and improve the bed structure by making the same of one piece, preferably of a single casting.

Other objects of my invention are to provide such a bed with integral elements forming bearings for the rotor of the motor and for the rotating elements which connect the motor with the driving wheels.

Another object of my invention is to provide guards for these various rotating parts made integral with the locomotive bed.

Another object of my invention is to form a portion of the motor frame integrally with the locomotive bed.

Similar objects of my invention are to form portions of the generator frame or housing integral with the bed and to form portions of the prime mover, such as an internal combustion engine, integral with the bed.

In the accompanying drawings which illustrate the invention—

Figure 1 is a side elevation of an electric locomotive embodying my invention but with its cab removed.

Figure 2 is a one-half longitudinal top view of the bed with the driving gear guards sectioned to reveal the gears which are also illustrated.

Figures 3, 4 and 5 are sections taken on lines 3—3, 4—4, and 5—5 of Figure 2.

Figure 6 illustrates a detail of the motor connection to the driving wheels.

Figure 7 is a fragmentary section corresponding to part of Figure 4 but illustrating

a modified form of the motor or generator frame.

Figure 8 illustrates a modified structure showing a different arrangement of driving motors.

The body of the bed comprises a pair of longitudinal members 1, illustrated as being of box cross section although other suitable forms may be used instead. The members are located on each side of the center line of the locomotive and equidistant therefrom and constitute the main supporting structure for the engine E, the generator G, and the motor M. Portions of members 1 project downwardly to form pedestals 2 for the locomotive drivers 3. A third longitudinal member 4 parallels members 1 and is spaced far enough from one of them to accommodate the driver wheels 3 between them. Member 4 is connected to the adjacent member 1 at intervals by transverse members 5 and intermediate these members 5, member 4 is provided with integral bearing elements 6 for the journals 8 of the gears 7. The entire bearing for the gear journal 8 may be formed integrally as indicated at 6 or the lower half of the bearing may consist of a removable cap. The gears 7 are flexibly connected to the driving wheels 3 by any suitable link mechanism such as illustrated in Figure 6. In this arrangement the segments S are mounted on the driving gear 7 at a and links 7 are connected to the segments 85 at b and to the driving wheel 3 at c, the gear 7 being perforated to permit substantial vertical movement of wheel 3 relative to the gear.

Abreast of motor M, member 4 extends upwardly to form a bearing element 9 for the journal 10 of the driving pinion 11 which is mounted on the rotor shaft 12 of the motor. As in the bearings for the driving gears 7, the entire bearing for the driving pinion 11 95 may be formed integrally with member 4 or the upper portion of the bearing may consist of a removable cap.

Intermediate the bearing element 6 for the driving gears the side member 4 is provided with bearing elements 13 for the journals of idler gears 14 which interconnect the adjacent driving gears 7 and enable all of the driving wheels to be operated by the single

motor. Preferably, the entire bearing for the idler journals is formed integrally by member 4 but these bearings, like the other bearings referred to, may be formed in two parts if desired.

Preferably each of the bearing elements 6, 9 and 13 are partially surrounded by integral flanged sections 15, 16 and 17, respectively, the same forming an outside guard for the 10 gear and the pinion mounted on the bearings.

In Figure 5 I illustrate the integral structure of the motor frame 18 and the longitudinal members 1 of the bed. By casting the parts it is possible to obtain this construction 15 which avoids the finishing and labor which would be necessary to assemble these parts if they were made separately, and also makes it possible to reinforce each of the members by the other, thereby eliminating the necessity of providing other reinforcing elements 20 and reducing the quantity of metal required for a given strength of bed and motor frame. The motor frame 18 serves as a transverse brace for the sills 1 and the latter reinforce 25 and rigidly position the motor frame. It is desirable to have the upper portion 18^a of the motor frame removable and this part of the frame is made separately and the portion integral with the bed provided with finished 30 pads 51 for attaching the removable part.

Similar details are embodied in the construction of the generator frame in which the lower portion 19 is formed integrally with the bed member 1, and forms a transverse brace 35 between them, and also extends above them and includes integral bearings 20 for the generator shaft 21. The upper ends of the generator frame portion 19 are provided with the finished bosses 22 for mounting the upper 40 portion 23 of the generator frame or housing. The generator frame portion 19 is provided with suitable slots 19^a which permit the ready insertion of windings for an alternating current generator. If a direct current generator 45 and motor are used the pole pieces may be formed integrally with the frame 19 as indicated at 52 in Figure 7.

The bed of the internal combustion engine E is also formed integrally with and forms a 50 part of the locomotive bed as best indicated in Figure 3 in which the engine crank case 24 is shown as supported above the level of sill 1 by means of vertical transverse webs 53 formed integrally with the bed and crank 55 case and the crank shaft bearings 26 are also formed integrally with the remainder of the casting and are suitably braced by extensions 27 of the crank case supporting ribs 25. Preferably the casting includes the upper 60 portion 28 of the crank case and the outer walls 29 of the water jacket, the same being finished to mount and fit the detachable cylinders 30 and the removable cylinder head 31. This figure also illustrates the integral 65 brackets 54 extending outwardly from the

sills and engine crank case and adapted to support the locomotive superstructure. Unit- 70 ing these brackets with the crank case and sills reinforces the engine and bed trans- versely and forms the inner ends of the brackets with deep sections to withstand the bracket loads.

At each end of the bed, integral end sills 32 connect the ends of members 1 and 4 and formed integrally with the end sills and 75 member 4 are the draft sills 33 and formed integrally with sills 1 are transverse members 34 mounted upon lead or trailing trucks 35 which are pivotally connected to the locomotive bed at 36.

Figure 8 illustrates a modified form of my invention in which each driving wheel 37 is driven by an individual motor 38, the upper portion 39 of each of the bearings for the driving gears 40 and the lower portion 41 of 80 each of the bearings for the driving pinions 42 being formed integrally with the longitudinal side member 43 of the bed, the sill 44 having integral pedestal jaws 45 formed thereon. In this construction the bearings 90 for the driving gears and pinions are completed by the removable caps 46 and 47, respectively. In this construction also the bed casting includes the lower portions 48 of the motor frames, but the upper faces of these 95 frames are finished with suitable pads 49 on which may be mounted the upper portions 50 of the motor frames or housings.

This type of construction is particularly 100 adapted for use in electric locomotives receiving current from feed wires or rails rather than locomotives which generate their own electric current.

In all forms of my construction described 105 the locomotive and various parts of the driving mechanism are formed integrally whereby play between cooperating elements is eliminated which is a marked advantage over an assembly of units in which the assembled elements frequently become loose and permit 110 relative movement of the parts. The integral construction enables me to provide strong sections at points where the depth or width of the parts is reduced because of the associated structure such as at the pedestal 115 recesses for the driving wheel journals and at points where the necessity of clearing the wheels and driving gears restricts the extensions of the bed.

These and various other advantages of my 120 invention are secured by the structure described and these advantages may be retained irrespective of variations in the details of the structure and I contemplate the exclusive use of all such modifications as fall in the 125 scope of my claims.

I claim:

1. In a locomotive, a plurality of driving 130 wheels on one side of the locomotive, driving gears for said wheels journaled independent-

- ly of the same, idler gears in mesh with said driving gears, and a driving pinion in mesh with one of said gears.
2. In a locomotive, a bed, a plurality of driving wheels on one side of said bed, wheel driving gears journaled on said bed, idler gears in mesh with said driving gears and connecting them and journaled on said bed, and driving means for one of said gears.
3. In a locomotive, a bed, a plurality of driving wheels on one side of said bed, wheel driving gears journaled on said bed, idler gears in mesh with said driving gears and connecting them and journaled on said bed, and a driving pinion in mesh with one of said gears and journaled on said bed.
4. In a locomotive, driving wheels, a bed, an internal combustion engine mounted on said bed over certain of said wheels, a generator mounted on said bed over other of said wheels and connected to said engine, a motor mounted on said bed over other of said wheels and connected to said generator and operatively connected to certain of said driving wheels, and operative connections between all of said driving wheels.
5. In a locomotive, a plurality of driving wheels, a bed mounted thereon, said bed having integral portions forming pedestals for said wheels and forming parts of a generator and motor structure for operating said wheels.
6. In a locomotive, a plurality of driving wheels, a bed mounted thereon, said bed having integral portions forming pedestals for said wheels and forming parts of an internal combustion engine and a generator and a motor for operating said wheels.
7. In a locomotive, a plurality of driving wheels, a bed mounted thereon, said bed having integral portions forming pedestals for said wheels and forming parts of a generator and motor structure, gearing connecting such structure to said driving wheels, and bearings for said gearing formed integrally with said bed.
8. In a locomotive, a plurality of driving wheels, a bed mounted thereon, said bed having integral portions forming pedestals for said wheels and forming parts of a generator and motor structure, gearing connecting such structure to said driving wheels, and bearings for said gearing formed integrally with said bed, there being a flexible driving connection between said gearing and one of said driving wheels.
9. In a locomotive, parallel longitudinal members forming the sides of a locomotive bed adjacent the inner faces of the driving wheels, and a longitudinal element located outside of said wheels and forming bearings for a driving gear and for a driving pinion, said element being integral with the adjacent member.
10. In a bed for a motor driven locomotive, a pedestal for a driving wheel, a bearing element for a driving gear located outside of the plane occupied by said wheel and formed integrally with said pedestal, and an integral bearing element for a driving pinion above said bearing element, the axes of said pedestal and bearings being in the same vertical plane.
11. In a bed for a motor driven locomotive, a pedestal for a driving wheel, a bearing element for a driving gear located outside of said pedestal and formed integrally therewith, and an integral bearing element for a driving pinion vertically above said gear bearing element, said bearing elements being united with each other independently of the bed.
12. In a bed for a motor driven locomotive, a pedestal for a driving wheel, a bearing for a wheel driving element, and a guard for said element extending below the level of said pedestal, all formed integrally with said bed.
13. In a bed for a motor driven locomotive, a pedestal for a driving wheel, a bearing outside of said pedestal for a driving gear for said wheel, a bearing above said gear bearing for a driving pinion for said gear, and a guard for said pinion and the lower portion of said gear formed integrally with said bearings.
14. In a bed for a motor driven locomotive, a pedestal for a driving wheel, a driving pinion bearing located above said pedestal and outside of the plane thereof, and a guard for the upper portion of said pinion formed integrally with said bearing and pedestal.
15. In a bed for a motor driven locomotive, a bearing element for a driving gear, and a flanged guard formed integrally with the bed and adapted to enclose the outer portion of said gear extending beyond said element.
16. In an electric locomotive, a bed casting including supporting wheel pedestals and having an electric generator frame element formed integrally therewith.
17. In an electric locomotive, a bed casting including supporting wheel pedestals and having an electric generator frame element formed integrally therewith and provided with parts for mounting one of the generator frame elements.
18. An electric locomotive bed casting comprising longitudinal members forming driving wheel pedestals at intervals, and transverse members connecting and reinforcing said longitudinal members and forming the lower portions of the frames of a motor and generator respectively.
19. A one piece casting comprising a locomotive bed and including an internal combustion engine crank case and a cylinder block adapted to mount detachable cylinder forming liners and a cylinder head.
20. A locomotive bed having sills and an

- internal combustion engine crank case formed integrally therewith and extending upwardly therefrom, and superstructure supporting brackets extending outwardly from
- 5 said sills and crank case and formed integrally therewith.
21. In a bed for a motor driven locomotive, a bearing element for a driving gear, a flanged guard formed integrally with the bed for
- 10 enclosing the lower portion of said gear, a second bearing element for a driving pinion spaced from said gear, and a flanged guard for enclosing the upper portion of said pinion, said guards being formed integrally with each other and with said elements. 15
22. An electric locomotive bed member including a generator frame element and an integral supporting wheel pedestal formed integrally therewith.

In testimony whereof I hereunto affix my 20
signature this 13th day of August, 1926.

KARL S. HOWARD.
